UNITED STATES PATENT OFFICE.

EMIL SPRENGER, OF GOLDACH, SWITZERLAND.

BLOCK-PRESS.

No. 923,595.

Specification of Letters Patent.

Patented June 1, 1909.

Application filed March 24, 1908. Serial No. 423,058.

To all whom it may concern:

Be it known that I, EMIL SPRENGER, a subject of the Swiss Republic, and resident of Goldach, Switzerland, have invented a 5 Block-Press, of which the following is a specification.

The subject of this invention is a press with revolving molds for manufacturing shaped bricks.

10 The accompanying drawings give several views of the invention.

Figure 1 is a front elevation of the press partly sectioned. Fig. 2 is a side elevation partly sectioned. Figs. 3-7 illustrate various 15 details.

Eccentric cams 4, 5, 6 are keyed to the shaft 3 as shown in Fig. 2. The shaft 3 is supported in the bearings 1 and 2. The cams 4 and 6 are fitted with detachable pressure rolls 6¹, whose axles lie in line with each other. The two cams 5 are quadrant shaped (only one is shown in Fig. 1) and, in order 20 to reduce friction to a minimum, are fitted with rollers which project beyond the surface of the quadrant.

A toothed wheel 8 is provided at each end of the shaft 3 between the bearings 1 and 2. The toothed wheel shown on the left in Fig. 1 has on its right side two diametrically opposite notches, in which a spring actuated pawl 26 fixed to the bearing 2, can engage. By this means the toothed wheel can be stopped after every half revolution. The 30 toothed wheels 8 carry molds 7^a, which are fastened between the two wheels and opposite to each other. These molds are divided into compartments 7, in each of which a close fitting press plate 12 can slide to and fro. Each opposite pair of these plates is 35 detachably fixed to a yoke 18, a pin *a* projecting into the back of the plate, fixing the same securely in position. All these yokes 18 are seated on two parallel shafts 19 which are provided with rollers 20, the distance between these shafts 19 being fixed and unadjustable.

In the position of the molds shown in Figs. 1 and 2, ("filling" and "discharging" 40 position) the upper shaft 19 lies with its rollers 20 on the upper surface of the cams 6. In this position the upper plates have been drawn back as far as possible, while the lower ones have been pushed as far down as possible. When the molds are in the upper 45 position, they are ready for filling and subsequent pressing after being closed at the

top. In the lower position, the molding boxes are emptied as described below. The cams 5 are inclosed by adjustable rods 22 which are rigidly connected by cross bars 22^a, so that when the toothed wheels 8 and molds 7^a revolve about the axis 3, one of the two cross bars 22^a slides over the rollers of the cam 5. By this means the rods 22, are prevented from moving till the wheels 8 55 have performed a quarter revolution starting from the position shown in Fig. 2. The rods 22 carry pins 23 at their ends. The mold shown at the top in Figs. 1 and 2 when filled with the material to be pressed, is covered 60 with the plate 25. The latter is then held securely by the lid 21, which also serves as a counter resistance against the force of the press. This lid is detachably secured to the rod 22, by hooks 24 which engage with the 65 pins 23, two of these hooks being revolubly fixed to pins 21^a on each side of the lid. The two hooks 24 shown in front of Fig. 1, and to the right in Fig. 2, have prolongations 24^a being thereby converted into levers. A small 70 driving wheel 14 is mounted outside the bearing 1 and is revolved by means of a crank 15. This wheel engages with the toothed wheel 13 on the shaft 13^a, and on this shaft, between the bearings, small 75 toothed wheels 9 are mounted, which engage with the large wheels 8 and revolve the latter together with the molds upon the fixed shaft 3.

The molds are filled by means of a hopper 80 16 closed at the bottom, which is movably mounted on two horizontal guide bars 16^a, (only one of which is shown) and is provided with a clearing plate 16¹. The hopper is filled and slid over the empty molds. 90 The bottom is then opened and the molds are filled, the hopper being then drawn back to the position shown in Fig. 2. During this latter operation any material projecting beyond the mold is smoothed down and the superfluous material wiped off by the plate 16¹.

When emptying the machine, a carriage 17 running on rails below the lid 21 is employed. This carriage is provided with a lever, revolubly about the axle 17^a and when 105 this is pressed down, the part 17¹ of the carriage to which is fixed the angle *c* is raised. The angle *c* now presses on the prolongation 24^a, so that the lid 21, (Fig. 2) on the left, is detached from the rods 22. If the lid 21 110 is now raised somewhat by the part 17¹, the two hooks 24 (Fig. 2 on the right) release

themselves from the pins 23 by their own weight, so that the lid is released from the rods 22 and lies upon the part 17¹ with the molded bricks. The part 17¹ is now returned to its original position, the carriage is drawn from under the machine, and the bricks are removed from the plate 25 and lid 21, while the latter are placed upon the upper molds which have been filled.

10 The machine is used as follows:—The upper mold is filled with material as described before and is then closed by the plate 25 and the lid 21. The pawl 26 is then disengaged and by means of the crank, the 15 toothed wheels are revolved in the direction of the arrow in Fig. 2, so that the molds 7^a are revolved through 180° about the shaft 3. During this movement of the molds, the upper shaft 19, (in Fig. 2) moves along the 20 rollers 6¹ of the cams 4 and 6 toward the right. In consequence all the press plates move outward, *i. e.* into the molds. During about a quarter of a revolution, the eccentric 25 5 holds the lid 21 securely against the mold by means of the lower cross bar 22^a, the rod 22, the pins 23 on the rod, and the hooks 24¹. In this way the material is pressed. During the continuation of the turning, the press plates under the action of the cams 6 30 move still farther out, but since the cams 5 allow the cross bar 22^a to make a movement downward and at the same time to the right, (Fig. 2) the material is not compressed any farther. The material and lid 35 are pressed farther and farther outward till at last the lid assumes the position shown dotted in Fig. 2. The lid 21 is then removed with the brick as described above, and the process is then repeated.

40 In order to make the brick out of materials which require different degrees of pressure, the rolls 6¹ on the cams 4 and 6 are made detachable so that larger or smaller rolls can be used, so that the distance traversed by the press plates is greater or less as desired. The cams 6 are also provided 45 with adjustable pieces 6², and according to the position of these pieces the plates sink to a greater or less degree in the molds when 50 in their highest position. By this means the capacity of the molds is altered since in the position shown in Fig. 2, the upper shaft 19 lies on the piece 6¹ and not on the surface of the cam 6. The amount of pressure 55 could also be regulated by inserting press plates of different thickness or by affixing liners to the press plates.

Having fully described my invention, what I claim and desire to secure by Letters 60 Patent is:—

1. Press for making shaped bricks, comprising in combination, a fixed shaft (3), bearings (1 and 2) supporting said shaft, eccentric cams (4, 5 and 6) fitted on said 65 shaft, pressure rolls (6¹) fitted to said cams

(4 and 6) anti-friction rollers fitted to said cam (5) a toothed wheel (8) at each end of said shaft, one of said wheels being provided with two diametrically opposite incisions, a spring pawl (26) engaging in said 70 incision, said pawl being fixed to said bearing, molds (7^a) fixed to said wheels (8), said molds being divided into compartments (7), a press plate (12) in each of said compartments, yokes (18) to which said press plates are detachably fixed, pins (a) on said yoke, projecting into holes in said plates, two shafts (19) carrying said yokes, rollers (20) on said shafts, adjustable rods (22) cross bars (22^a) rigidly connecting 80 said rods, said rods carrying pins (23) at their ends, a plate (25) covering said molds when filled, a lid (21) covering said mold, hooks (24) on said lid, which engage with said pins (23), said hooks (24) having prolongations (24¹) a driving wheel (14) mounted outside said bearing (1), a crank (15) by which said wheel is revolved, a toothed wheel (13) a shaft (13^a) supporting said wheel, toothed wheels (9) on said 90 shaft, engaging with said wheels (8), a hopper (16) for filling said molds, a plate (16^a) fitted to said hopper, guide bars (16^b) on which said hopper slides, a carriage (17) for emptying said molds, a lever fixed to 95 said carriage, whereby a part (17¹) of said carriage is raised, an angle (c) attached to said part (17¹) and engaging with said prolongation (24¹) for detaching said lid, substantially as described and shown.

2. Press for making shaped bricks, comprising in combination, a fixed shaft (3), bearings (1 and 2) supporting said shaft, eccentric cams (4, 5 and 6) fitted on said shaft, pressure rolls (6¹) fitted to said cams 105 (4 and 6) anti-friction rollers fitted on said cam (5) a toothed wheel (8) at each end of said shaft, one of said wheels being provided with two diametrically opposite incisions, a spring pawl (26) engaging in said 110 incision, said pawl being fixed to said bearing, mold (7^a) fixed to said wheels (8), said molds being divided into compartments (7), a press plate (12) in each of said compartments, said press plates being made detachable and of various thicknesses in order to be able to use material requiring varying degrees of pressure, yokes (18) to which said press plates are detachably fixed, pins (a) on said yoke, projecting into holes in 115 said plates, two shafts (19) carrying said yokes, rollers (20) on said shafts, adjustable rods (22) cross bars (22^a) rigidly connecting said rods, said rods carrying pins (23) at their ends, a plate (25) covering said molds when filled, a lid (21) covering said mold, hooks (24) on said lid, which engage with said pins (23), said hooks (24) having prolongations (24¹) a driving wheel 120 (14) mounted outside said bearing (1), a 125

crank (15) by which said wheel is revolved, a toothed wheel (13) a shaft (13^a) supporting said wheel, toothed wheels (9) on said shaft, engaging with said wheels (8) a hopper (16) for filling said molds, a plate (16¹) fitted to said hopper, guide bars (16^a) on which said hopper slides, a carriage (17) for emptying said molds, a lever fixed to said carriage, whereby a part (17¹) of said carriage is raised, an angle (c) attached to said part (17¹) and engaging with said pro-

longation (24¹) for detaching said lid, substantially as described, and shown, and for the purpose set forth.

In testimony whereof I have hereunto set 15 my hand in the presence of two subscribing witnesses.
